UNITED STATES PATENT OFFICE.

GARRET B. OSTERHOUT, OF PROVIDENCE, RHODE ISLAND, ASSIGNOR TO WILLCOX & GIBBS SEWING MACHINE CO., OF NEW YORK, N. Y., A CORPORATION OF NEW YORK.

SEWING-MACHINE.

1,134,483.

Specification of Letters Patent.

Patented Apr. 6, 1915.

Application filed September 30, 1913. Serial No. 792,676.

To all whom it may concern:

Be it known that I, GARRET B. OSTERHOUT, a citizen of the United States of America, and resident of Providence, Rhode Island, have invented a new and useful Improvement in Sewing-Machines, which improvement is fully set forth in the following specification.

This invention relates to sewing machines, and more particularly to parts designated as the "loop-shedder" and "loop-spreader" in machines of the character disclosed in the patents to S. Borton, No. 1,041,574, and A. A. Merritt, No. 1,041,652, both dated October 15th, 1912.

The objects and character of the invention may be most readily understood by reference to the accompanying drawings illustrating what is now regarded as the preferred embodiment thereof, and wherein—

Figure 1 is a vertical sectional view through the end of the work-arm of the machine and stitch-forming parts associated therewith; Fig. 2 is a similar view with the parts in a different position of their movement; Fig. 3 is a detail view of the feed-member on which the loop-shedder blade or lip is formed; Fig. 4 is a similar detail in which a rod or wire forms the loop-shedding edge; and Figs. 5 and 6 are detail views of the loop-spreader.

10 is a part of the end of a hollow work-arm, upon the upper surface of which is mounted a work-plate or throat-plate 11.

12 is a main presser-foot, 13 an auxiliary presser-foot, and 14 needles (of which there are four, only one showing in the drawings) working through a slot in the main presser-

40 foot 12.

15 is a looper lever, only the forward end of which is shown, on which is pivotally mounted a looper carrier 16, to which there is fixed four loopers 17 (only one of which 45 shows in the drawings) adapted to co-operate with the four needles 14 respectively.

18 is a loop-check and needle-guide fixed to the side wall of the hollow work-arm 10 and positioned just above the end of looper 50 lever 15 and the looper carrier 16 thereon.

The parts thus far described in detail are of substantially the same construction as the corresponding parts of the Merritt Patent No. 1,041,652, before mentioned, to 55 which reference is made for a more detail

explanation of their construction and operation. As in said Merritt patent, the drawings herein show a double feed, that is to say, two separate feed devices or surfaces which slightly differ in their relative movements, one acting on the work before it reaches the needles to give what is known as a "fulling feed," and the other acting on the work after it has passed the needles to give the stitch feed.

As illustrated in Figs. 1 and 2, 20 is the fulling feed member and 21 the stitch feed member; each has a shank or foot by which it is secured by a screw 22 (see dotted lines Fig. 1) to the forward end of a 70 feed lever, there being one such lever for each feed member. The means whereby such feed levers and their associated feed members are given different relative movements which may be relatively adjusted and 75 varied for different characters of work being done by the machine or for different thicknesses of goods and length of stitch, may be readily understood by reference to the aforesaid Merritt patent. A dotted line ellipse 80 23 in Figs. 1 and 2 illustrates the approximate path of movement of the stitch feed member 21.

In the aforesaid Merritt patent, there is shown a loop-shedder in the form of a projecting flange or lip secured to the under side of the throat-plate across the rear edge of the needle opening therethrough. In accordance with the present invention, the loop-shedder is associated and movable with the 85 stitch-feed member 21, and in Figs. 1, 2 and 3 is shown in the form of a slightly inclined lip or blade 24 extending from the toothed portion of the feed member 21 rearwardly 90 toward the needles and across the opening 95

25 in said feed member through which the needles operate. It has been found that the movement imparted to the stitch-feed member 21 is a desirable movement for a loop-shedding blade, such as 24, and that by imparting such movement to the loop-shedder it acts more effectively and with greater certainty in pushing the loops of needle-thread off the loopers 17 at the proper time in the 100 stitch-forming cycle than when the loop-shedder is an immovable part secured to some fixed portion of the machine. In said Merritt patent there is shown a loop-spreader having at its forward end three horizontally projecting teeth adapted to engage the 110

looper threads to properly spread the loops thereof to be entered by the descending needles. In accordance with the present invention, three teeth 26, 27 and 28 are formed 5 to project downwardly from the under side of the end of the loop-spreader 29 and are inclined slightly toward the direction (indicated by the arrow 30 in Fig. 5) in which the end of said loop-spreader 29 moves in engaging 10 the looper-threads and spreading the same for the needles to enter the loops thereof. With this formation of the teeth, it is found that they engage, hold, and release the looper-threads with greater certainty of 15 action at the high speeds at which machines of this type are operated. At its opposite end, the loop-spreader 29 has a circular opening engaging around a circular flange 31 about an opening 32 through tail-piece 33. 20 A screw 34 rigidly secures the spreader 29 to the tail-piece 33. A pivot-screw 35 passes through the opening 32 into a bracket 36 which is rigidly secured to and projects from the side wall of the hollow work-arm. A 25 depending roller 37 works in a cam-shaped groove of a part 38 fixed by a screw 39 to the looper-lever 15. The elliptical movement of the forward end of the looper-lever 15 carrying with it the part 38 with its cam-shaped groove engaging the roller 37, imparts to the loop-spreader 29 a pivotal movement about the screw-pivot 35 causing the toothed end of the loop-spreader to swing back and forth transversely to the work-arm, 30 such movement being properly timed with relation to the movements of the loopers and needles.

In Fig. 1 with the parts moving in the directions indicated by arrows, the points of 40 the needles have penetrated the work, the loopers 17 are moving in a direction to disengage themselves from the loops of needle-threads, the loop-spreader with its teeth engaging the looper threads is moving in a direction 45 to spread the loops in said threads, the stitch-feed member 21 is moving toward the needles, and the edge of the loop-shedder blade 24 is in contact with the loops of needle-threads. In Fig. 2, these parts have 50 moved further in the same directions, until the edge of blade 24 is about to disengage the needle-thread loops from the loopers and the needles have descended into loops of looper threads spread by the spreader 29. 55 Instead of a blade or lip 24, the loop-shedder applied to the stitch-feed member may take the form of a rod or wire 40, Fig. 4, which will provide the necessary edge or part to engage the needle-thread loops and 60 push them off the loopers. Furthermore, the movable loop-shedder of this invention may be embodied in forms other than those illustrated by way of example, and said loop-shedder need not necessarily be a part of a 65 feed-member.

What I claim is:—

1. The combination with one or more loopers and means for imparting thereto loop-taking and releasing or shedding movements; of a movable loop-shedder adapted 70 to contact loops of thread on the looper or loopers and by its movement to push said loops toward the point of the looper or loopers while the latter are making their releasing or shedding movement; and means 75 for actuating said loop-shedder.

2. The combination with one or more loopers and means for imparting thereto loop-taking and releasing or shedding movements; of a movable loop-shedder adapted 80 to contact and push toward the point of the looper or loopers loops of thread on the latter, and means for actuating said loop-shedder causing it to advance toward the point of the looper or loopers simultaneously 85 with the receding or releasing movement of the latter.

3. The combination with one or more thread-carrying needles; of one or more loopers coöperating with said needles; means 90 for imparting to said looper or loopers movements for taking loops of the needle thread and for releasing or shedding said loops; and a movable loop-shedder and means actuating the same to contact and push toward 95 the point of the looper or loopers loops of needle-thread thereon.

4. The combination with one or more loopers and means imparting thereto loop-taking and releasing or shedding movements 100 approximately parallel to the line of feed; of a loop-shedder movable approximately parallel to the line of feed and adapted to contact and by its movement push toward the point of the looper or loopers loops of 105 thread on the latter; and means for actuating said loop-shedder.

5. The combination with one or more loopers and means for imparting thereto loop-taking and releasing or shedding movements; of a feed-member having a part 110 adapted in the movement of said member to contact and push toward the point of the looper or loopers loops of thread on the latter.

6. The combination with one or more loopers and means for imparting thereto loop-taking and releasing or shedding movements; of a feed-member having thereon a loop-shedding lip adapted in the movement of said member to contact and push toward the point of the looper or loopers loops of thread on the latter. 115

7. The combination with a plurality of appropriately driven needles; of means—including a plurality of loopers and a loop-spreader having downwardly projecting thread-engaging teeth—adapted to project loops of stitch-forming looper threads through loops of thread projected by each 120 125 130

of two needles from one side of the seam and to extend said loops of looper-threads laterally across the seam into position for another needle to form stitches there-through; and driving connections for said parts.

8. The combination of a plurality of appropriately driven needles; a throat-plate; one or a plurality of loopers and driving 10 connections for operating the same in a plane approximately parallel to the throat-plate; and a loop-spreader having down-

wardly projecting thread-engaging teeth and driving connections for moving the same in a plane approximately parallel to the 15 throat-plate on an axis approximately perpendicular to said throat-plate.

In testimony whereof I have signed this specification in the presence of two subscribing witnesses.
